The ornamental design for a laser level as shown and described.

DESCRIPTION

1. Laser level

1.1 : Perspective

1.2 : Perspective

1.3 : Left

1.4 : Right

1.5 : Front

1.6 : Back

1.7 : Perspective

A distinctive feature of the design is the appearance of the housing; this applies in particular to the trapezoidal shape of the device casing and the layout of the recesses in it; the layout of the buttons and indicators is characteristic as well; the bottom side of the design is not characteristic and is therefore only partially shown in one view.
